UNITED STATES PATENT OFFICE.

JOHN B. BECKER, OF NEW YORK, N. Y.

PROJECTILE.

1,146,780.

Specification of Letters Patent. Patented July 20, 1915.

Application filed October 31, 1914. Serial No. 869,501.

To all whom it may concern:

Be it known that I, JOHN B. BECKER, a citizen of the United States, and a resident of the borough of Manhattan, city of New York, in the county and State of New York, have invented certain new and useful Improvements in Projectiles, of which the following is a specification.

My invention relates to explosive projectiles and refers particularly to a projectile in which its impact against a target releases a quantity of explosive material capable of explosion at a point below the point of impact.

My invention is broadly a projectile comprising an impact head and an explosive-carrying chamber in engagement therewith, and means for causing their disengagement upon impact of the projectile against a target, upon such disengagement the explosive-carrying chamber falling downwardly, and means for exploding the explosive in the chamber after the disengagement at a point below the point of impact. The disengagement may be caused by any means, mechanical, explosive or otherwise, and the explosion may be accomplished by any suitable method, the essential element of my invention being the explosion below the point of impact between the projectile and the target.

One object of my invention is a projectile capable of exerting its explosive force below the water line of a vessel, even if the projectile itself strikes the vessel above the water line.

Another object of my invention is a projectile which is capable of ejection from a gun, or other projecting medium, situated above the water, the explosive force of the projectile being exerted below the water line of a target against which it is impinged.

Another object of my invention is a projectile of great carrying radius, in that it may be fired much greater distances to produce a destructive result than the present known devices, thus possessing the valuable advantage of successful application without a near approach to the target.

Another object of my invention is a projectile in which the destructive power is not dependent upon the complete piercing of the armor of a vessel accompanied by an explosion of the projectile after it has passed into the vessel; but in which the destructive power is exerted near the bottom of the vessel, below the water line, due to the impact

of the projectile against the side of the vessel above or below the water line.

With the above, and other objects in mind, I have devised a projectile which is simple in construction, inexpensive to manufacture, positive in operation, which may be propelled through the air for great distances, in which the destructive force of the explosion is not proportionate to the force of the impact and which causes an explosion below the water line of a target even if the projectile strikes the target above the water line.

The sides of the modern battle-ship are so heavily armored that little damage can be done them above the water line except by projectiles having enormous impact force sufficient to pierce them, the explosive effect being delayed until the projectile has passed through the hull into the interior of the ship, the simple rupture of the hull above the water line being usually of little serious effect. The most vulnerable part of a battle-ship is that portion below the water line, where the armor is not so thick and resistant or where the ship is not protected and where a rupture is most dangerous on account of the resultant inflow of water. For this reason, sub-marine torpedoes have proven the most effective projectiles and have received wide application. Torpedoes of this character have, however, several serious objectionable characteristics, the chief one of which is the limited range at which they may be successfully launched, on account of the resistance of the water and the effect of currents; and the complicated machinery incident to self-propelling torpedoes renders them liable to become disordered and ineffective. The most successful present known method of using torpedoes is by means of sub-marine boats on account of the possibility of their near approach to a target without discovery but their radius of action is short, the number of torpedoes which they can carry is limited, and on account of the resistant properties of the water and the comparatively small target presented by the ship's bottom they are compelled to approach very close to the ship in order to properly place and explode a torpedo.

By means of my device all of the above objections are overcome and increased efficiency is the result of its application.

My projectiles may be fired much greater distances than marine-torpedoes as they are

projected through the air and may be projected from any power or caliber gun, the length of range being limited only by the capacity of the gun. A much larger target is presented in their use, as it is not limited to the portion of the vessel under water as in the use of marine-torpedoes, the destructive force of my device being exerted under the water even if the projectile strikes the vessel above the water. My device contains no propellers or complicated machinery, and on account of its simplicity of construction is not liable to become inoperative. My device is absolutely free from any possibility of accidental explosion during its handling. Further, as my projectile may be ejected from guns situated above the water line, as upon ships, it is evident that a very considerable number may be carried and that their radius of action from a base is limited only by the radius of action of a battle-ship that carries them.

These and other features of my invention which contribute to the convenience, safety and efficiency of my projectile are shown in the accompanying drawings wherein several desirable embodiments of my invention are illustrated and wherein the reference characters of this description are applied to like parts in the several views.

Figure 1 is a longitudinal cross section of one form of my device. Fig. 2 is a cross-section through the line 2—2 of Fig. 1. Fig. 3 illustrates the comparative positions of the elements of Fig. 1 after impact against a target. Fig. 4 illustrates the comparative positions of the elements of a modification of my device after impact against a target.

In the form of my invention as illustrated in the drawings, the separation of the explosive-carrying chamber from the head is effected by the explosion of an explosive material, due to the impact of the projectile against a target. The head 9 is composed of a metallic substance—as steel, preferably solid, capable of piercing a target when impinged against it. The head 9 has a recess 10 around and near its rearward end. A cap 11 fits tightly around the head 9 and within the recess 10 and extends outwardly and rearwardly from the head 9 and is capable of release from the head when subjected to outward longitudinal pressure. The rear wall 12 of the cap 11 has a threaded orifice 13 through which a threaded percussion cap 14 may be inserted from the outside. In order to prevent premature explosion during the handling of the projectile, the percussion cap 14 need not be inserted until just previous to the introduction of the projectile into the gun. Within the cap 11, and carried thereby, is a separate explosive-carrying chamber 15 containing an explosive 16 which may be inserted through

the opening shown closed by the threaded plug 17 in the rear wall 18. This rear wall 18 has another opening 19, through which a fuse 20 is inserted, the fuse extending outwardly from the chamber 15 and also inwardly therein, ending in a suitable fulminating cap packed and primed into the explosive 16. The compartment 21' between the rear wall 18 of the explosive-carrying chamber 15 and the rear wall 12 of the cap 11 contains an explosive material capable of explosion by means of the percussion cap 14, the explosive 16 within the chamber 15 being capable of explosion by means of a fulminating cap upon the fuse 20. The percussion cap 14 is so situated that it will be exploded by the impact of the projectile against a target. The recess 10 in the head 9 is of such a size and character that it will support the cap 11, with its contents, during the projection and flight of the projectile but will allow of the separation of the head 9 and the cap 11, when the explosive in the compartment 21' is exploded by the action of the percussion cap 14, causing an outward longitudinal pressure. The forward end or nose of the head 9 should be pointed to allow it to penetrate or pierce the target, and it may carry a series of circular recesses 21, 21, the object of which will be explained later.

In operation, when the projectile, formed and loaded as described, is impinged against a target 22, the concussion will fire the percussion cap 14, exploding the explosive in the compartment 21', driving the cap 11 outwardly or longitudinally from the recess 10 in the head 9 and allowing the explosive-carrying chamber 15 to drop downwardly. At the same time the explosion in the compartment 21' will ignite the fuse 20, which communicating with the explosive 16 will explode the latter. It is evident that by use of a time fuse at 20, the explosion within the chamber 15 may be regulated to occur at any predetermined time after the impact of the projectile against a target. The impact of the projectile against a target will hold it momentarily in position in the target to allow the chamber 15 to drop perpendicularly and this momentary retention may be facilitated by using the recesses 21, 21 in the nose of the head 9. It is evident from the above description that when the projectile strikes a target as the side of a vessel, above the water line, the explosive-carrying chamber 15 will drop downwardly beneath the water and that a properly timed fuse at 20 will cause an explosion within the chamber when said chamber is beneath or close to the bottom of the vessel.

In the modification of my device shown in Fig. 4 the rearward end of the head 9 contains a chamber 29 carrying a chain 30, one end of which is affixed to the head 9 at 130

31, the other end being affixed to the explosive-carrying chamber 15 at 32. It is evident that by means of this chain element the time fuse need not be so accurate as the 5 chain will sustain the chamber 15 until it is exploded, in Fig. 4 the explosive-carrying chamber being shown as suspended beneath the water line 33.

I do not limit myself to the particular 10 size, shape, arrangement of parts or means for releasing the explosive-carrying chamber, shown and described, all of which may be varied without going beyond the scope of my invention as described and claimed.

15 What is claimed, is:

1. A projectile comprising: a recessed head, a separate explosive-carrying chamber, means separable from the head and the explosive-carrying chamber for sustaining 20 the said chamber in alinement with the head, a compartment so situated that a pressure therein will release the explosive-carrying chamber from the head allowing the chamber to fall downwardly, an explosive with- 25 in said compartment, and means for exploding the explosive within said compartment releasing the explosive-carrying chamber from the head, allowing the said chamber to fall downwardly.

30 2. A projectile comprising a recessed head, a cap fitting in and sustained within the recess in the head, a separate explosive-carrying chamber within the cap, a compartment between the end of the explosive- 35 carrying chamber and the end of the cap, an explosive within said compartment, means for exploding the explosive in said compartment, for releasing the cap and explosive-carrying chamber from the head 40 due to said explosion.

3. A projectile comprising: a recessed head, a cap fitting in and sustained within the recess in the head, a separate explosive-carrying chamber within the cap, a compartment between the end of the explosive- 45 carrying chamber and the end of the cap, an explosive within said compartment, means for exploding the explosive in said compartment for releasing the cap from the 50 head and allowing the explosive-carrying chamber to fall downwardly, and means for suspending the explosive-carrying chamber a predetermined distance from the head.

4. A projectile comprising a head recessed 55 at its rearward end, a cap sustained by its

engagement within said recess and capable of separation therefrom by internal longitudinal pressure, a separate explosive-containing chamber within the cap abutting upon the rear of the head and forming a compartment between itself and the rear wall of the cap, an explosive within said compartment, means for exploding said explosive upon impact of the projectile against a target, said explosion releasing the cap 60 from the head, and allowing the explosive-carrying chamber to drop downwardly free from the head and the cap.

5. A projectile comprising a head recessed at its rearward end, a cap sustained by its 70 engagement within said recess and capable of separation therefrom by internal longitudinal pressure, a separate explosive-containing chamber within the cap abutting upon the rear of the head and forming a 75 compartment between itself and the rear wall of the cap, an explosive within said compartment, a fuse connecting the explosive in the explosive-carrying chamber with the explosive in the compartment, means for 80 exploding the explosive in the compartment upon impact of the projectile against a target, said explosion releasing the cap from the head, and allowing the explosive-carrying chamber to drop downwardly free from 85 the head and the cap.

6. A projectile comprising a head recessed at its forward and rearward ends, a cap sustained by its engagement within the recess at the rearward end of the head and 90 capable of separation therefrom by internal longitudinal pressure, a separate explosive-containing chamber within the cap abutting upon the rear of the head and forming a compartment between itself and the rear 95 wall of the cap, an explosive within said compartment, means for exploding said explosive upon impact of the projectile against a target, said explosion releasing the cap from the head, and allowing the explosive-carrying chamber to drop downwardly free from the head and the cap.

Signed at New York city in the county of New York and State of New York, this 30th day of October, 1914.
